DAVID E. KATZ, OF NEW YORK, N. Y., ASSIGNOR TO BAYER, PRETZFELDER, AND MILLS,
INCORPORATED, OF NEW YORK, N. Y.

BRACELET CLASP.

Application filed June 23, 1928. Serial No. 287,841.

My invention relates to improvements in bracelet clasps and the object of the invention is to devise a simple and effective clasp for the ends of the bracelet which will surely hold them in place and which will also be adjustable so that the length of the bracelet will be capable of being shortened or lengthened within the limits of adjustability of such clasps.

10 My invention consists of a clasp constructed and arranged all as hereinafter more particularly described and illustrated in the accompanying drawing in which:—

Fig. 1 represents a plan view of a clasp constructed according to my invention, showing the parts so positioned that the bracelet is of the greatest possible length.

Fig. 2 is a side view thereof.

Fig. 3 is a similar view to Figure 1 showing 20 the parts arranged so that the length of the bracelet is shortened.

Fig. 4 is a side view thereof.

Fig. 5 is a side view showing the tongue member of the clasp inserted into one of the 25 slots in a member secured to one end of the bracelet, and

Fig. 6 is a plan view of the tongue member showing an expansible slot therein.

Like characters of reference indicate corresponding parts in the different views.

30 1 is a member having formed integrally therewith means 2 for securing it to one end 3 of the bracelet. 4 is a tongue member hinged to the free end of the member 1 and 35 provided with the expansible slot 5 terminating in a circular end 6.

7 is a headed stud extending upwardly from the member 1 intermediately of the 40 length of the same and provided with the neck 8.

9 is a member having formed integrally therewith means 10 for securing it to the other end 11 of the bracelet, said member 9 being provided with the transverse slots 12.

45 The hinged end of the tongue member 4 is provided with a foot 13 which engages the end of the member 1 when such tongue member is swung substantially at right angles to such member 1, as is illustrated in Figure 5 50 of the drawing, thus facilitating the insertion of the tongue member into a slot in the member 9.

My device is actuated as follows:—

Assuming that the two parts of the clasp

are detached from one another the tongue is 55 preferably swung into the position illustrated in Figure 5 and the member 9 applied thereto by inserting the tongue member 4 into the required slot 12, depending upon what adjustment is required. If the bracelet is to 60 be of its extreme length the tongue member 4 is inserted into the end slot 12 as illustrated in Figures 1 and 2, whereas if it is to be shorter such tongue member can be inserted into any other of the slots 12 or into the end 65 slot 14, thus giving four length adjustments for the bracelet. Each of the slots 12 are of sufficient width to receive the stud member 7 when the bracelet is in its shortened positions, that is when the tongue member 4 is 70 inserted in the opening 14 or the adjacent transverse slots 12 the stud 7 is received in the middle or outer transverse slots 12 respectively. Having inserted the tongue member 4 into the required slot it is turned 75 down onto the member 1 with the member 9 positioned between the members 4 and 1. When this is done the head of the stud 7 will be forced into the circular end of the expansible slot 5 and as such circular end 6 of the 80 slot is of slightly smaller diameter than the head of the stud such slot will be expanded by forcing down the member 4 against the member 1 until the head of the stud passes through the end 6 of the slot. Such slot will 85 then contract so that its end 6 will encircle the neck 8 of the stud, thus constituting an effective catch for holding the parts of the clasp together.

From the above description it will be apparent that I have devised a simple and effective bracelet clasp which will be exceedingly strong in construction and which will effectively secure the ends of the bracelet together. Moreover, I have devised a clasp which will 95 lend itself to being adjusted to vary the length of the bracelet with the minimum of trouble.

What I claim as my invention is:

1. A bracelet clasp comprising a pair of 100 members, each having means at one end for attachment to the corresponding end of a bracelet, a tongue hinged to the other end of one of said members and adapted to be passed through one of a plurality of transverse slots formed in the other member, a stud mounted on the tongue carrying member adapted to interlock with the edges of an 105

expansible opening formed in the tongue, the width and arrangement of the slots being such that when the tongue is passed through certain of the slots the stud will be received through a slot other than that through which the tongue passes.

2. A bracelet clasp as recited in claim 1 in

which the stud and the expansible opening are positioned intermediate the length of the tongue carrying member and the tongue respectively.

In testimony whereof he has affixed his signature.

DAVID E. KATZ.
